UNITED STATES PATENT OFFICE.

THORVALD J. PETERSEN, OF NEW YORK, N. Y., ASSIGNOR TO THE GLOBE LIGHTING FIXTURE MFG. CO., OF BROOKLYN, NEW YORK, A COPARTNERSHIP.

DESIGN FOR A LOOP FOR LIGHTING FIXTURES.

Application filed February 4, 1928. Serial No. 25,177. Term of patent 3½ years.

To all whom it may concern:

Be it known that I, THORVALD J. PETERSEN, a citizen of the United States, residing at New York city, county of New York, and State of New York, have invented a new, original, and ornamental Design for a Loop for Lighting Fixtures, of which the following is a specification, reference being had to the accompanying drawing, forming part thereof, in which—

Fig. 1 is a front view, showing my new design; and

Fig. 2 is a side elevation of the same.

I claim:

The ornamental design for a loop for lighting fixtures, as shown.

THORVALD J. PETERSEN.
